UNITED STATES PATENT OFFICE.

IDA C. HUNT, OF WOOLDRIDGE, MONTANA.

CORER.

1,135,185.

Specification of Letters Patent. Patented Apr. 13, 1915.

Application filed March 4, 1914, Serial No. 822,393. Renewed February 12, 1915. Serial No. 7,811.

To all whom it may concern:

Be it known that I, IDA C. HUNT, citizen of the United States, residing at Woolridge, in the county of Valley and State 5 of Montana, have invented certain new and useful Improvements in Corers, of which the following is a specification.

My invention relates to corers and more particularly to an apple corer.

10 The primary object of my invention is to provide an apple corer which will core the apple and at the same time will not permanently engage the core and become clogged by the same.

15 Another object of my invention is a provision of a novel cutting blade having a novel means in connection therewith for mounting the same upon the shank for preventing longitudinal or rotary movement of 20 the blade on the shank.

25 A further object of my invention resides in the provision of an improved apple corer that is simple in construction, efficient in operation, and one that can be manufactured and placed upon the market at a minimum cost.

30 Other objects as well as the nature, characteristic features, and scope of my invention will be more readily understood in the following description taken in connection with the accompanying drawings and 35 pointed out in the claims.

In the drawings: Figure 1, represents a perspective view of my invention. Fig. 2, 35 represents a transverse sectional view of the same taken on line 2—2 of Fig. 1.

Referring more particularly to the drawings in which similar reference numerals designate corresponding parts throughout 40 the different views, I provide a piece of wire, which in this instance comprises a shank 1, having one end thereof bent upon itself in a substantial triangular form to constitute a handle 2, and the opposite end 45 thereof being sharpened to provide a point 3 for insertion in the core of an apple. It is to be understood that the shank may be formed of any desirable material that is capable of being flattened without breaking.

50 The shank has secured thereto, between the handle 2 and the point 3, a blade 4, the latter consisting of a substantial semicircular piece of sheet metal, the straight longitudinal edge 5 of which is wrapped about

the shank as at 6 and flattened as at 7 to 55 prevent the same from having longitudinal or rotary movement upon the shank. The blade 4 is now curved spirally about the shank and tapers gradually toward the point 3 as at 8. By this particular arrangement the curved edge 9 of the blade is positioned in spiral relation to the shank, the curved edge being beveled to form a cutting edge in order that the corer may be easily inserted into an apple for coring the 60 same.

The operation of my device is as follows: The handle 2 is engaged by one hand of the user and is inserted in the core of an apple which is held by the other hand of 70 the user. The handle is now turned and at the same time forced downward into the apple about the core. By this, it can be easily seen that the core will be cut, and, from the peculiar construction and arrangement of the blade, will remain in the apple 75 where it can be easily removed by a slight shake or knock after the blade has been removed.

It will be noted from the construction 80 shown and described that this corer can be easily cleaned and is capable of being dried without great danger of cutting the hands of the user, thus preventing the accumulation of rust or dirt and providing a sanitary 85 corer.

From the foregoing it will be seen that I have provided an apple corer which will not become clogged when the apple is being cored and also one that is simple in 90 construction, efficient in operation, and because of its few parts and the simple manner of connecting the same, can be manufactured and put upon the market at a minimum cost.

95 It will be obvious to those skilled in the art to which this invention relates that modifications may be made in detail without departing from the spirit and scope of my invention.

Having thus described my invention what I claim and desire to secure by Letters Patent is:

1. In a device of the character described, a shank, a blade carried by said shank, and 105 said blade being curved spirally about said shank, substantially as described and for the purpose set forth.

2. In a device of the character described, a shank, a semicircular blade secured to said shank, said blade being curved spirally about said shank, and a cutting edge formed upon said shank.

3. In a device of the character described, a shank, a handle formed upon said shank, the opposite end of said shank being pointed, a semicircular shaped blade secured to said shank between said handle and the pointed end of said shank, said blade being curved about said shank and tapering toward the pointed end of said shank, and the outer edge of said shank being arranged in spiral relation with said shank.

4. In a device of the character described, a shank, a handle formed upon one end of said shank, the opposite end of said shank being pointed, and a blade carried by said

shank, the outer edge of said blade being 20 bent in a substantial spiral shaped form.

5. In a device of the character described, a single piece of wire comprising a shank, a handle formed upon one end of said shank, the opposite end of said shank being 25 pointed, a substantially semicircle blade, the curved edge of said blade being sharpened, the longitudinal edge of said blade being wrapped about said shank and flattened, and said blade being arranged in a substantial 30 spiral shaped form about said shank.

In testimony whereof I affix my signature in presence of two witnesses.

IDA C. HUNT.
